UNITED STATES PATENT OFFICE.

SOLOMON KARPEN, OF CHICAGO, ILLINOIS, ASSIGNOR TO S. KARPEN & BROS., OF CHICAGO, ILLINOIS, A CORPORATION OF WEST VIRGINIA.

COUCH OR SOFA.

1,213,380.

Specification of Letters Patent. Patented Jan. 23, 1917.

Application filed August 9, 1915. Serial No. 44,600.

To all whom it may concern:

Be it known that I, SOLOMON KARPEN, a citizen of the United States, residing at Chicago, in the county of Cook and State 5 of Illinois, have invented new and useful Improvements in Couches or Sofas, of which the following is a specification.

This invention relates particularly to a combined couch and bed, or a combined 10 sofa and bed; and the primary object is to provide a simple and cheap construction, which is thoroughly adapted to the purpose.

The invention is illustrated in its preferred embodiment in the accompanying 15 drawings, in which—

Figure 1 represents an end elevational view of a couch-bed embodying the invention, the structure being shown in open condition; Fig. 2, a broken sectional view on 20 a large scale, taken as indicated on line 2 of Fig. 1; Fig. 3, a broken sectional view illustrating the manner in which the bed-sections are connected; Fig. 4, a broken detailed view of the brace employed for holding 25 the seat in standing position; Fig. 5, a view partly in section and partly in end elevation, showing the couch in closed condition; and Fig. 6, a section taken as indicated at line 6 of Fig. 1.

In the form illustrated, the structure 30 comprises a base-box or frame A, having its front corners equipped with short standards or angle irons A'; a rearwardly swinging seat B; and a folding bed C, mounted on 35 the standards A'.

The standards A' are firmly secured in the front corners of the box A, being spaced with relation to the end members 1 of the 40 box by cleats 2. The upper ends of the standards project a short distance above the upper edge of the box.

The seat B has a frame 3, which is adapted to rest upon the upper edge of the box A when the structure is closed. The 45 seat is connected with the rear portion of the box by hinges 4. A folding brace, or braces 5, connects the frame of the seat with the box A. The spring 6 serves to hold the brace 5 in the straightened position. 50 When the seat is in the standing position. The lower front member of the brace 5 is provided with a shoulder 7, which abuts against the shoulder at the end of the upper member of the brace in the manner

shown in Fig. 4, when the brace is straight- 55

The folding-bed C comprises a rear bed section 8, an intermediate spacing section 9, and a front section 10. The intermediate or spacing section 9 is connected by pivots 60 11, with short folding standards 12, whose lower ends are connected, by pivots 13, with the upper ends of the standards A'. The short angle bars comprising the spacing section 9 are joined by a truss 14. A wire 65 fabric or flexible bed bottom 15 is stretched on the folding bed frame.

At each end of the bed is employed a pair of links 16 and 17, connected respectively with the pivot 11 and the pivot 13, 70 the links approaching and being connected together by a pivot 18. The pivot 18 is connected, by a short link 19, to the adjacent end member of the outer bed section 10; and a link 20 connects the link 19 with 75 a corresponding leg 21 with which the outer bed section is provided.

The rear bed section 8 is supported in the elevated position by links 22, whose lower ends are connected by pivots 23, to 80 the end members 1 of the box A. The rear upper ends of the links 22 are equipped with studs 24, slidable in the slits 25 with which the end members of the rear bed section 8 are provided. Links 26 connect the 85 links 22 to the links 17; and springs 27 connect the intermediate bed section 9 with the rear portions of the links 26. The arms of the rear and front bed sections are connected with the intermediate section by 90 pivots 28, as shown in Fig. 3. The joints are such as to afford abutting shoulders, as indicated at 29, when the bed is in extended condition; and when the bed is folded, the ends of the members forming 95 the intermediate bed section 9 afford shoulders 30, which engage the horizontal flanges of the arms of the bed sections 8 and 10, thus holding the folded sections of the bed in U form.

Assuming the structure to be in closed condition, it may be converted to bed form by swinging the seat B rearwardly to the standing position and then swinging the bed upwardly and forwardly. The operation of lifting the bed is assisted by the springs 27. In the folded condition of the structure, the short folding standards 12

100

105

depend from the pivots 13. In the operation of opening the bed the members 12 are swung to a position above the pivots 13, the links 22 are caused to elevate the rear bed section, and the links 21 are extended through the medium of the links 20. It will be noted that the links 26 cause the links 22 to raise the rear bed section and afterward afford connections between the front bed section and the rear bed section which serve to prevent collapse of the structure when the bed is occupied.

The structure described is simple, cheap, and well adapted to its purpose. The arrangement is such that when the bed is folded and the seat lowered, the frame of the seat will inclose the upper portions of the standards A' and the upper (front) bed section.

20 What we regard as new and desire to secure by Letters Patent is:

In a structure of the character set forth, the combination of a main box frame provided at its front corners with fix-

edly secured standards, folding standards mounted thereon, an intermediate bed section mounted on said folding standards, front and rear bed sections pivotally connected with the intermediate bed section, a pair of links at each end of the bed structure connected with the pivots at the ends of the folding standards, a link connecting each of said pairs of links with the outer bed section, folding legs connected with the outer bed section, links joining said legs to said second named links, links connected with the end members of the box frame and serving to elevate the rear bed section, actuating links for said last named links, connected with said pairs of links, and springs connecting the intermediate bed section with and tending to elevate the links which support the rear bed section.

SOLOMON KARPEN.
